UNITED STATES PATENT OFFICE.

WILLIAM W. HOLLOWAY, OF WHEELING, WEST VIRGINIA, AND HENRY KIELBERG,
OF MARTINS FERRY, OHIO, ASSIGNEES TO WHITAKER-GLESSNER COMPANY, OF
WHEELING, WEST VIRGINIA, A CORPORATION OF WEST VIRGINIA.

RADIANT GAS HEATER.

Application filed July 26, 1922. Serial No. 577,722.

To all whom it may concern:

Be it known that we, WILLIAM W. HOLLOWAY and HENRY KIELBERG, citizens of the United States of America, and residents, respectively, of Wheeling, county of Ohio, and State of West Virginia, and Martins Ferry, county of Belmont, and State of Ohio, have invented certain new and useful Improvements in Radiant Gas Heaters, of which the following is a specification.

This invention relates broadly to gas heaters of the radiant type, and more particularly to a sheet-metal heating stove of that character in which tubular radiants of earthen composition are employed.

The primary object of the invention is to provide an efficient open-front radiant gas heater composed wholly of sheet metal and possessing a construction which is strong, rigid and durable and which may be manufactured at relatively small cost.

A still further object is to provide a stove or heater of the character referred to having a form and construction which adapts it to be snugly packed for storage and shipment in partially knocked-down form in individual corrugated paper or cardboard cartons of ordinary rectangular form with its detached parts closely nested within and protected against injury by the lower part of the heater casing.

With these and other important objects in view, the invention resides in the features of construction, arrangement of parts and combinations of elements which will hereinafter be fully described, reference being had to the accompanying drawings, in which—

Figure 1 is a top plan view of a stove or heater constructed in accordance with our invention;

Figure 2 is a vertical section of the same; Figure 3 is a horizontal section on line 3—3, Fig. 2;

Figure 4 is a front elevation of the one-piece stove casing;

Figure 5 is a view of said casing partially in top plan and partially in horizontal section; and—

Figure 6 is a section on line 6—6, Fig. 4. Referring to said drawings, 1 indicates the rear wall and 2 the side walls of a stove casing of substantially rectangular form in horizontal section, said casing being herein

shown as formed of a single piece of sheet metal. An outwardly pressed terminal bead 55 or roll 3 is formed on the lower edge of the rear wall 1, and similar beads or rolls 4 are formed on the lower edges of the side walls 2, said rolls being designed to receive in clamping relation thereto the panels 5 and 6 of reinforcing devices constituting a sub-structure which is disclosed in our companion application for Letters Patent, Serial No. 577,726, and which serve as mountings 60 for legs 7 and 8 whereby the stove is supported.

The front edge portions of the side walls 2 are turned inward at right angles, forming panel-like facings 9 which present the appearance of corner posts, said facings having rearwardly directed terminal flanges 10 to which are bolted or otherwise attached the front edges of divergently inclined shields or plates 11 which occupy positions in suitably spaced relation to the side walls, said 70 plate serving to shield said side walls and to provide an intermediate space for the circulation of air. Said plates 11 are disposed upright and have their lower edges shaped to conformably seat upon a horizontal sheet-metal plate 12 which constitutes a support for a plurality of aligned radiant tubes 13, and upon a fender plate 14 which has its rear edge mounted upon an inclined flange 12^a of said radiant support and its front 75 edge seated upon the horizontal ledge 15^a formed by an inturned flange provided on the upper edge of a low sheet-metal cross panel 15 which joins the corner posts 9 adjacent to the lower ends of the latter. Said 80 parts 12^a and 15^a are best illustrated in Fig. 2, which shows a sectional view taken substantially on line 2—2, Fig. 3.

An inturned terminal flange 1^a is formed on the upper edge of the rear wall 1, and 85 similar flanges 2^a and 9^a are formed on the upper edges of the side walls 2 and posts 9, respectively. Seated upon said terminal flanges is a top plate or cover 16 which is pressed upwardly adjacent to its rear edge portion to form an upstanding roll-like rib 16^a. The rear edge of said cover is bent forward beneath said rib 16^a and is then bent back upon itself in clamp-like form for closely embracing the flange 1^a of the rear 100 wall 1. Said cover has an approximate U-

shape in top plan, being designed to overlie that portion of the casing interior located rearward of the fender plate 14 and to overlie and close the spaces between the side walls 2 and the shield plates 11, while leaving open the space in front of the radiants 13.

A downturned flange 16^b formed upon the front edge of the cover complements a vertical transverse depending flange 17^a for shielding from view that portion of the casing interior located at and above the level of the upper ends of the radiants. Said flange 17^a is formed upon the front edge portion of a horizontal plate 17 which is mounted upon the upper edge portion of an upright sheet metal back wall 18. Said back wall is located at a suitably spaced distance rearward of the radiants 13, being seated upon the radiant support 12, and has a forwardly pressed rib 18^a against which the backs of the upper end portions of said radiants rest. The upper end of the back wall is turned rearward to form a horizontal leg 18^b which is suitably attached to the rear wall 1 of the casing.

Located rearward of said back wall 18 is a suitably inclined plate or deflector 19 whereby heat radiated rearward by said back wall is deflected away from the rear casing wall. The upper and lower edge portions of said deflector have legs 19^a and 19^b attached to the rear casing wall, as shown. Heat entering the space between said deflector and said rear wall 1 finds its way past the ends of said deflector to the spaces between the shield plates 11 and the side walls 2, whence it escapes through suitable apertures or perforations 20 provided in the rib portion of the cover 16. To facilitate circulation of air for carrying the heat from said space between the deflector and the rear casing wall, draft openings or perforations 21 are provided in the lower leg 19^b of the deflector and other perforations 22 are provided in the rear portion of the radiant support 12.

Likewise heat between the deflector 19 and the back wall 18 finds its way to the spaces between the shield plates 11 and the end walls 2 and thence escapes through said apertures 20. Circulation for removing such heat is facilitated by the perforations 22 of the radiant support and also by the provision of perforations 23 in the leg 18^b of the back wall 18.

The portions of the cover 16 which overlie the post-like or boxing-like front corners of the stove casing are preferably surmounted by knobs 24 designed to give the structure an ornamentally finished appearance.

A burner 25 is supported beneath the radiant support 12, the same being designed to furnish a readily combustible mixture of gas and air to the radiants 13 through aper-

tures 26 provided in said support and embraced by the base portions of said radiants.

From the foregoing description it will be understood that we have devised a sheet-metal heater of open-front radiant type having a construction not only affording great strength, rigidity and durability, but also providing for ready and convenient assembling of parts. Furthermore, it will be apparent that, due to the fact that it is composed almost wholly of parts formed of sheet metal, it is relatively inexpensive to manufacture.

The heater structure described is adapted to be partially knocked down and packed for storage and shipment in individual cartons of ordinary rectangular form. The legs 7 and 8 have only to be removed to render the heater structure of substantially rectangular form for snugly fitting such a box or carton, and these legs, together with the individually wrapped radiants, may obviously be wrapped and stored within the casing either in the open space located in front of the back wall or that beneath the radiant support.

What is claimed is—

1. In a radiant gas heater, a sheet metal casing consisting of a rear wall and side walls, said side walls having their front edge portions turned inwardly, a horizontal radiant support located within said casing, said support having burner apertures adapted to be embraced by radiants seated thereon, a fender extending forward from said support, a back wall seated upon said support rearward of said apertures, and upright shield plates overlying said support and said fender, said plates being interposed between the inturned edge portions of the side walls and said back wall.

2. In a radiant gas heater, a sheet metal casing consisting of a rear wall and side walls, said side walls having their front edge portions turned inwardly, a horizontal radiant support located within said casing, said support having burner apertures adapted to be embraced by radiants seated thereon, a fender extending forward from said support, a back wall seated upon said support rearward of said apertures, and upright shield plates seated upon said support and said fender at a distance from said side walls, said plates being interposed between said back wall and said inturned edge portions and attached to the latter.

3. In a radiant gas heater, a sheet metal casing consisting of a rear wall and side walls, said side walls having their front edge portions turned inwardly and provided with a rearwardly directed terminal flange, a horizontal radiant support located within said casing, said support having burner apertures adapted to be embraced by radiants seated thereon, a fender extending forward from

said support, an upright sheet metal back wall extending upward from said support rearward of said apertures, shield plates interposed between said back wall and said 5 terminal flange, a sheet metal deflector located intermediate said back wall and the rear wall of the casing, and a cover superposed on said casing, said support and said cover having therein openings permitting of 10 an upward circulation of air between the casing walls and the back wall and shield plates.

4. In a radiant heater, a one-piece sheet metal casing comprising a rear wall, side 15 walls and post-like front corners, said corners being located inwardly of said side walls, said casing members having outwardly pressed rolls at their lower edges, means engaged with said rolls constituting a casing 20 reinforcing structure and forming a mounting for supporting legs, a radiant support disposed horizontally within said casing, a back wall seated upon said support, upright plates interposed between said 25 back wall and the inner portion of the post-like corners of the casing, said plates being superposed upon said support, and a cover for said casing.

5. In a radiant heater, a sheet metal casing comprising a rear wall and side walls, said side walls having their front edge portions shaped to form upright angular post-like corner members located inwardly of said side walls, a panel connecting the lower 30 portions of said members, leg mountings constituting means whereby the lower corner portions of said casing walls are reinforced, a horizontal radiant support located within the lower rear part of the casing, said support having burner openings 35 therein, an inclined fender extending from said support to the top of said panel, a back wall seated upon said support rearward of said openings, upright shield plates closing 40 the end spaces between said back wall and said corner members of the casing, and a cover of approximately U-shape mounted upon the top of the casing.

6. In a radiant heater, a sheet metal casing comprising a rear wall and side walls, said side walls having their front edge portions shaped to form upright angular post-like corner members located inwardly of said side walls, a panel connecting the lower 50 portions of said members, leg mountings constituting means whereby the lower corner portions of said casing walls are reinforced, a horizontal radiant support located within the lower rear part of the casing, 55 said support having burner openings therein, an inclined fender extending from said support to the top of said panel, an upright metal back wall located rearward of said burner openings, upright shield plates closing 60 the end spaces between said back wall and

and said corner members of the casing, a heat deflector located rearward of said back wall, and a cover mounted upon said casing walls, said cover and said radiant support having draft openings in the rear portions 70 thereof.

7. In a radiant heater, a sheet metal casing comprising a rear wall and side walls, said side walls having their front edge portions shaped to form upright angular post-like corner members located inwardly of said side walls, a panel connecting the lower portions of said members, leg mountings constituting means whereby the lower corner portions of said casing walls are reinforced, a horizontal radiant support located within the lower rear part of the casing, said support having burner openings therein, an inclined fender extending from said support to the top of 80 said panel, an upright metal back wall located rearward of said burner openings, upright shield plates closing the end spaces between said back wall and said corner members of the casing, a heat deflector located rearward of said back wall, and a cover mounted upon said casing walls, said cover and said radiant support having draft 85 openings in the rear portions thereof, said cover being shaped to conform substantially to the spaces intermediate the shield plates and the side walls of the casing and the space located between the front edge of said support and the rear casing wall.

8. In a gas heater, a sheet-metal casing consisting of a rear wall and side walls, a horizontal sheet metal radiant support mounted within said casing and having burner openings therein, radiants seated upon said support over said openings, upright sheet-metal shield plates located inward of the side walls of the casing, a sheet metal back wall located rearward of said burner openings, the rear edges of said shield plates being attached to said back wall, said back wall having a horizontal forwardly pressed rib disposed in bracing relation to said radiants, said casing side walls and said shield plates extending a substantial distance forward of said radiants and having their front edge portions connected one to the other, and a cover surrounding said casing, the rear and lateral edges of said cover being attached to the walls of said casing and the front portion of said cover being shaped to conform to the portions of the shield plates located forward of the radiants.

9. In a gas heater, a sheet-metal casing consisting of a rear wall and side walls, a horizontal sheet metal radiant support mounted within said casing and having burner openings therein, radiants seated upon said support over said openings, upright sheet-metal shield plates located in- 125

ward of the side walls of the casing, a sheet metal back wall located rearward of said burner openings, the rear edges of said shield plates being attached to said back wall, said casing side walls and said shield plates having their front end portions connected one to the other at a substantial distance forward of said radiants, and a cover fitted upon said casing over the spaces located laterally of the shield plates and rear-

ward of the plane of the front faces of said radiants.

In testimony whereof we affix our signatures in presence of two witnesses.

WILLIAM W. HOLLOWAY.
HENRY KIELBERG.
